(57) **CLAIM**

I claim the ornamental design for a wallet, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a front view of a wallet, according to my new design;

FIG. 2 is a front, right side perspective view thereof;

FIG. 3 is a rear view thereof;

FIG. 4 is a rear, left side perspective view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front view of a second embodiment of the wallet of FIG. 1;

FIG. 10 is a front, right side perspective view thereof;

FIG. 11 is a rear view thereof;

FIG. 12 is a rear, left side perspective view thereof;

FIG. 13 is a top plan view thereof;

FIG. 14 is a bottom plan view thereof;

FIG. 15 is a right side elevational view thereof; and,

FIG. 16 is a left side elevational view thereof.

The broken lines shown in the drawings illustrate portions of the wallet that form no part of the claimed design.
